UNITED STATES PATENT OFFICE.

JOHN E. BELL, OF NEW YORK, N. Y., ASSIGNOR TO THE BABCOCK & WILCOX COMPANY,
OF NEW YORK, N. Y., A CORPORATION OF NEW JERSEY.

WATER-TUBE BOILER.

1,129,538.

Specification of Letters Patent. Patented Feb. 23, 1915.

Application filed July 8, 1907. Serial No. 382,588.

To all whom it may concern:

Be it known that I, JOHN E. BELL, of New York city, in the county and State of New York, have invented a new and useful Water-Tube Boiler, of which the following is a full, clear, and exact description, reference being had to the accompanying drawings, forming part of this specification, in which—

10 Figure 1 is a sectional side elevation showing one form of boiler constructed in accordance with my invention; and Figs. 2 and 3 are diagrammatic sectional side elevations showing modified forms.

15 The invention relates to boilers of the transverse-drum, multiple-bank, serial-pass type, and is designed to provide an improved arrangement of baffling whereby the gases are closely held in contact with the tubes. It is also designed to increase the amount of heating surface exposed to radiant heat.

20 A further object is to decrease liability to the formation of steam pockets in the front bank of tubes and insure a high velocity of the gases.

25 In Fig. 1 of the drawings, I show my invention as applied to a four-drum, three-bank Stirling type of boiler. In this case, 2, 3 and 4 are upper transverse steam and water drums, connected by banks of tubes 5, 6 and 7 with a lower transverse mud drum 8. Two or three transverse mud drums may be employed, either or all of which may be connected by rows of tubes. The tubes may be curved at their ends, or the drums may be struck up so as to employ straight tubes. In the form shown, 9 are water circulators connecting the water spaces of the two front 30 upper drums, and 10 and 11 are steam circulators leading the steam from the front and rear drums to the middle drums, whence it is taken off. I have shown the front bank of tubes as leaning forwardly over the combustion chamber, this combustion chamber being freely open in its upper portion so as to expose the front wall of the setting to the heat, no roof or arch being used over the grate. Such arch may, however, be employed within the scope of my broader 35 claims relating to the baffling. In this form, the refractory baffling consists of a baffle 12 extending upwardly from the mud drum between the first and second row of the front bank of tubes. The next baffle 13 ex- 40 tends from the upper steam and water drum downwardly along the rear of the front bank of tubes, being preferably supported by tension rods 14. The third baffle 15 extends along the rear of the second bank of tubes with an opening over its upper end, a shelf 16 being employed to hold the gases within the rear bank 7 in their last down pass to the off-take port 17. I have shown the water as fed into the rear upper drum through pipe 18. In the operation of the boiler, the gases flow up the front row of tubes of the front bank, thence down among the front bank of tubes, thence up the middle bank, and down the rear bank to the outlet flue. With the form of furnace shown, the size of the combustion chamber is increased, the smoke reduced to a minimum, and increased economy obtained. The front wall of the boiler setting will become highly 45 heated, and the gases will be exposed to heated fire brick to substantially the same extent as with the arch or roof construction commonly employed in boilers of this type. In the present form, the front row of tubes 50 is exposed to the radiating surface formed by the front wall, thus increasing the amount of radiant heat received by the tube-heating surface. As the furnace gases enter the front bank of tubes near their upper ends, the steam will be most rapidly generated in this upper portion of the tubes, and has only a short distance to travel into the front upper drum. This gives less liability 55 to the formation of steam pockets and possible reversing of circulation. The tubes of the front bank which are in the rear of the front baffle receive the gases near their upper ends at the first contact thereof, and the major portion of the steam in these tubes is 60 generated in their upper parts; whereas with the old style baffling, the most of the steam was produced in the lower portions of the tubes where the steam might readily pass to the mud drum rather than flow up through the tubes to the steam and water drum. In the front row of tubes of the front bank, the production of steam in the lower portion is of course not diminished in 65 the form of Fig. 1, but as there is more steam generated in the upper portion of the bank there is less liability for reversal of circulation. It also gives a narrow pass through which the gases must flow at high 70 velocity, insuring the maximum amount of 75 80 85 90 95 100 105 110

heat being absorbed per square foot of heating surface. The furnace may be employed for coal, oil sprays, or any other desirable fuel.

6 In Fig. 2 I show a form similar to that of Fig. 1, except that the baffle 12^a is composed of hollow bricks or tiles which incloses the front row of tubes. In this case the front row will only be directly exposed to the 10 gases above the end of the baffle. In this form parts similar to those of Fig. 1 are designated by similar numerals with the letter "a" applied.

15 In Fig. 3 I show a form similar to that of Fig. 1, except that the front baffle is obtained by bending portions of the second row of tubes 5^b into the spaces between the front set of tubes along the baffling portions. The upper portions of the second row 20 being in their normal position will allow the gases to flow through after they reach the upper end of the forwardly bent portions.

25 By the words "baffle element" in my claims, I intend to cover any form of baf-
fing device, not only such as those I have shown, but all other forms. I also intend, in my claims, to cover the structure whether one or more mud drums or lower water spaces is used.

29 The tubes may be straight or curved; the number of steam and water drums or mud drums may be varied; two or more banks of tubes may be used; and many other changes may be made without departing 35 from my invention.

I claim:—

1. The combination of a steam boiler furnace having a combustion chamber at the front thereof and a drum in the lower portion thereof, series of tubes extending upwardly from the drum, the front series being located at the rear of the combustion chamber with the front setting wall facing it, a baffle extending upwardly from the drum at the front of the front series of tubes and constituting the back of the combustion chamber, and alternately downwardly and upwardly projecting baffles behind the first mentioned baffle and providing means for directing the products of combustion longitudinally of the series of tubes behind the first mentioned series, the last heating surface over which the products pass consisting of a water heating surface; substantially as described.

2. The combination of a steam boiler furnace having a combustion chamber at the front thereof and a drum in the lower portion thereof, series of tubes extending upwardly from the drum, the front series being located at the rear of the combustion chamber with the front setting wall facing it, a baffle extending upwardly from the drum at the front of the front series of tubes and constituting the back of the com-

bustion chamber, and alternately downwardly and upwardly projecting baffles behind the first mentioned baffle and providing means for directing the products of combustion longitudinally of the series of tubes 70 behind the first mentioned series, the major portion of the water heating surface in the first downward pass of the gases consisting of tubes of the front bank, and the last heating surface over which the products 75 pass consisting of a water heating surface, substantially as described.

3. The combination of a steam boiler furnace having a combustion chamber at the front thereof and a transverse drum in the lower portion thereof, a plurality of upper transverse steam and water drums having sets of tubes extending downwardly to the lower drum, the front series being located at the rear of the combustion chamber with the front furnace setting wall facing it, a baffle element constituting the back of the combustion chamber and extending upwardly from the drum in the front portion of the front set of tubes, and terminating short of the front steam and water drum, and baffling in rear of the front baffle element and arranged to direct the gases downwardly and upwardly among the succeeding sets of tubes, the last heating surface over which the products pass consisting of a water heating surface, substantially as described.

4. The combination of a steam boiler furnace having a combustion chamber at the front thereof and a mud drum in the lower portion thereof, a plurality of upper transverse steam and water drums having series of tubes extending downwardly to the mud drum, the front series being located at the rear of the combustion chamber with the front setting wall facing it, a baffle element constituting the back of the combustion chamber and extending upwardly in front of tubes in the front series, and terminating short of the front steam and water drum, and baffling in the rear of the front baffle element and arranged to direct the gases upwardly and downwardly among the succeeding sets of tubes, said baffling directing the gases downwardly in the last pass 110 among the rear set of water tubes, substantially as described.

5. The combination of a steam boiler furnace having a combustion chamber at the front thereof and three upper transverse 120 steam and water drums connected by banks of tubes to a lower mud drum, the front bank of tubes being located at the rear of the combustion chamber with the front setting wall facing it, a baffle extending upwardly at the front of the front bank and forming the back of the combustion chamber and terminating short of the front steam and water drum, and succeeding baffles arranged to direct the gases alternately down- 125 130

- wardly and upwardly, said baffles being arranged to direct the gases upwardly among the tubes of the middle bank and downwardly among the water tubes of the rear bank, substantially as described. 5
6. The combination of a steam boiler furnace having a combustion chamber at the front thereof, three upper transverse steam and water drums, the two front steam and water drums having water circulators extending between them, three banks of tubes connecting said steam and water drums with a lower mud drum, the front bank of tubes being located at the rear of the combustion chamber and facing the front setting wall, a baffle element forming the back of the combustion chamber and extending upwardly at the front of the front bank and terminating short of the upper drum, and 10 succeeding baffling arranged to direct the gases alternately downwardly and upwardly, said baffling directing the gases downwardly among the tubes of the last or third bank, substantially as described. 15
7. In a vertical water tube boiler, the combination with a combustion chamber, transverse upper steam and water drums, a lower mud drum, and a plurality of banks of upwardly extending tubes connecting the same, the front bank inclining upwardly and forwardly over the combustion chamber and facing the front setting wall, of a baffle extending upwardly and longitudinally along the front of the first bank from the lower 20 end thereof and terminating short of the upper end thereof, said baffle constituting the rear wall of said combustion chamber and the exit from said combustion chamber being over said baffle, and among the upper 25 end of the first bank of tubes, and another baffle extending longitudinally along the rear of said first bank from the upper end thereof, and terminating short of the lower end, said baffle thereby compelling the heated gases to first strike the upper end of the first bank and then traverse the said first bank longitudinally downwardly from its upper to its lower end and counter to the circulation in the tubes of said bank, substantially as described. 30
8. The combination with a steam boiler furnace having a combustion chamber at the front thereof and a drum in its lower portion, and series of tubes extending upwardly from the drum, the front series being located at the rear of the combustion chamber and facing the front setting wall, of a baffle extending upwardly in front of tubes of the front series, and constituting the back of the combustion chamber, and alternate downwardly and upwardly projecting baffles behind the first mentioned baffle and providing means for directing the products of combustion along 35 the series of tubes behind the first mentioned
- series, the heating surface of the first downward pass consisting mainly of water tubes of the front bank, and the furnace setting having an outlet for gases adjacent to the lower portion of the rear bank of water tubes, substantially as described. 70
9. The combination of a steam boiler furnace having a substantially unobstructed combustion chamber at the front thereof, and a drum in its lower portion, a series of tubes extending upwardly from the drum, the front series being located at the rear of the combustion chamber and facing the front setting wall, a baffle device at the back of the furnace cutting off the lower portion of the majority of the tubes of the front bank from the furnace and having its upper part located between the rows of tubes of the front bank, and succeeding baffles for the other series of tubes, the major part of the heating surface of the first bank lying in the first downward pass of the gases, substantially as described. 80
10. The combination, with a steam boiler furnace of the general Stirling type having a combustion chamber at the front thereof and a drum in the lower portion thereof and series of tubes extending upwardly from the drum, the front series being located at the rear of the combustion chamber, of a baffle 90 extending upwardly from the drum at the front of the front series of tubes and constituting the back of the combustion chamber, and alternately downwardly and upwardly projecting baffles behind the first mentioned baffle and providing means for directing the products of combustion longitudinally of the series of tubes behind the first mentioned series, substantially as described. 95
11. A transverse-drum serial-pass multiple-bank boiler having the banks provided with baffles, the bank with which the flame and hot gases first contact supporting a baffle in front of some of the tubes thereof, 100 said baffle forming the rear of the combustion chamber; substantially as described. 105
12. A transverse-drum serial-pass multiple-bank boiler having the banks provided with baffles, the bank with which the flame and hot gases first contact supporting a baffle at the front thereof, said baffle forming the rear of the combustion chamber; substantially as described. 110
13. A transverse-drum serial-pass multiple-bank boiler having the banks provided with baffles, the bank with which the flame and hot gases first contact supporting a baffle at the front of said bank and having a baffle at the rear of said bank; substantially as 115 described. 120
14. A steam boiler having a plurality of upper transverse steam and water drums, a lower transverse mud-drum, banks of tubes connecting said upper and lower drums, a 125

- 4
- furnace, the first bank of tubes having two baffles supported by the tubes, one of said baffles being at the front and extending upward to the upper part of the bank and forming the rear wall of the furnace combustion chamber, and the second of said baffles being at the rear of the first bank of tubes to cause the gases to flow downward over the first bank; substantially as described. 10
15. A transverse-drum serial-pass multiple-bank boiler having the banks provided with baffling, the bank with which the flame and hot gases first contact being provided with a baffle at the front and extending upward from the mud drum for directing the gases to the upper part of the bank, and with a baffle at the rear to direct the gases downward, and a baffle extending upward from the mud drum at the rear of the middle bank of tubes to direct the gases upward along the tubes of said bank; substantially as described. 15
- 20
25. A steam boiler having a plurality of upper transverse steam and water drums, a lower transverse water drum, banks of tubes connecting said upper and lower drums, a furnace, the front bank having a baffle supported upon a row of tubes at the front there-
- of to direct the gases to the upper part of the front bank, and succeeding baffles to cause the gases to flow over the tubes of the remaining banks, and finally downward over the tubes of the rear bank; substantially as described. 30
- 35
17. A steam boiler having a plurality of upper steam and water drums, a lower water drum, banks of tubes connecting said upper and lower drums, a furnace, the front bank having a baffle supported upon a row of tubes at the front thereof to direct the gases to the upper part of the front bank, succeeding baffles to cause the gases to flow upward along the tubes of the middle bank, a baffle shelf between the middle and rear banks to direct the gases to the upper part of the tubes of the rear bank, and a flue outlet or opening for the escape of the gases near the lower part of the rear bank to cause the gases to flow downward substantially over the entire surface of the tubes of the rear bank; substantially as described. 40
